(57) **CLAIM**

We claim the ornamental design for a desk top battery charger for a portable phone, as shown.

DESCRIPTION

FIG. 1 is a top, front and right side perspective view of a desk top battery charger for a portable phone showing our new design.

FIG. 2 is a top, rear and right side perspective thereof.

FIG. 3 is a left side elevational view thereof.

FIG. 4 is a top plan view thereof.

FIG. 5 is a rear side elevational view thereof; and,

FIG. 6 is a bottom side plan view thereof.
